Primary Examiner—Ian Simmons*Assistant Examiner*—Charles Hanson(74) *Attorney, Agent, or Firm*—Foley & Lardner LLP(57) **CLAIM**

We claim the ornamental design for a double walled metallic bowl, as shown and described.

DESCRIPTION

FIG. 1 is a top perspective view of one embodiment of a design for a double walled metallic bowl;

FIG. 2 is a front elevational view thereof, the rear elevational view, left end elevational view and right end elevational view being the same as the front elevational view shown;

FIG. 3 is a top plan view thereof;

FIG. 4 is bottom plan view thereof; and,

FIG. 5 is a sectional view thereof taken along line 5—5 of FIG. 3.

The ornamental design which is claimed is shown in solid lines in the drawings. The broken lines in the drawings are for illustrative purposes only and form no part of the claimed design.
